UNITED STATES PATENT OFFICE.

JOSEPH H. GLAUBER, OF CLEVELAND, OHIO.

PIPE-CO尤LING FOR BROKEN WATER-CLOSET BOWLS.

SPECIFICATION forming part of Letters Patent No. 606,536, dated June 28, 1898.

Application filed December 24, 1897. Serial No. 663,411. (No model.)

To all whom it may concern:

Be it known that I, JOSEPH H. GLAUBER, a citizen of the United States, residing at Cleveland, in the county of Cuyahoga and State of Ohio, have invented certain new and useful Improvements in Pipe-Couplings for Broken Water-Closet Bowls; and I do declare that the following is a full, clear, and exact description of the invention, which will enable others skilled in the art to which it appertains to make and use the same.

My invention relates to pipe-couplings for broken water-closet bowls; and the invention consists in the construction and combination of parts, substantially as shown and described, and particularly pointed out in the claims.

In the accompanying drawings, Figure 1 is a vertical sectional elevation of a water-closet bowl in which the horn is supposed to have been broken off and connection is made by means of my improved coupling, which likewise is shown in section. Fig. 2 is a perspective view of my new coupling complete as it appears when in use. Fig. 3 is a perspective view of the sleeve alone, and Fig. 4 is a like view of the detachable hook alone.

In this art, as well as in others, simplicity of construction and cheapness of manufacture are important considerations, and these advantages are combined in this instance with what are deemed to be material improvements from a purely structural point of view. Thus, referring to the drawings, A represents a section of water-closet bowl without the usual horn at the rear, this member presumably having been broken off by accident or otherwise. Otherwise the bowl is in good condition; and in order to be utilized some special means of coupling or connection for the water-supply pipe must be made. To this end

I employ the coupling mechanism here shown, or substantially in this form, and consisting in this instance of the sleeve B, adapted to occupy the position relatively as shown, the thimble or connection C, the packing-ring E, and the inside fastenings, as hereinafter described.

Now it will be noticed that the bowl has the usual apron, shield, or cover D over the water-inlet opening and coming down somewhat below the same, so as to perfectly cover and conceal said opening and leaving only a small

space relatively between the apron and the wall of the bowl. This space is so slight that coupling mechanism cannot be introduced therethrough, nor can the hand be entered therein to assist in making the connections. Indeed, sometimes this space is entirely closed, except relatively small openings at intervals. Hence all the connecting mechanism must be constructed to enter and engage from without the bowl. To this end and to make a simple, cheap, and efficient coupling, I have made the connection for entering the bowl substantially as shown, the said sleeve B having hooks or fingers 2 and 4, respectively, to make the connection. The hook 2 in this instance is integral with the sleeve B, and the hook 4 is a separate member or part constructed to lock upon the sleeve B and to serve the same purpose when coupling is effected as would a rigid hook in that position.

To secure the hook 4, the sleeve has a channel or groove 5 lengthwise in its outside at a point preferably, but not necessarily, opposite the hook 2; and one or more small holes, cavities, or the like 6 to be engaged by the projection 7 on the said hook. The holes 6 and projections 7 might be reversed on the parts and serve the same purpose—that is, the holes might be in part 4 and the projection on the sleeve. By having more than one hole 6 the part 4 can be adapted to walls of bowls varying in depth or thickness, as often occurs, and the said parts are then tightened up by connection C.

The hook 4 is made shallow enough to come below the engaging portion of the threads around the sleeve and which cross the same, and thus the hook or hook-shank, and thus I avoid the expense of threading the back of the hook and yet secure it tightly locked in place. This construction also facilitates the connecting up of the parts with the bowl and affords a construction whereby said parts can as readily be removed from the bowl should occasion require. When the hook 4 has been entered and engaged for service, the projection 7 is locked in one of the holes 6, and then these parts are ready to have the thimble or connecting member C brought into place. The said member C as here shown, answers the purpose of a tightening-nut to draw sleeve B and its hooks into place and to se-

cure the packing E, as well as of a coupling for the pipe connections beyond. (Not shown.)

A number of material advantages are obtained by this invention, among which are the extreme simplicity and cheapness of construction, the readiness with which the parts can be placed in working position, and the thoroughly good connection they make. It will also be observed that the sleeve and its hooks are adapted to any thickness of wall in the bowl, because it is immaterial what position the sleeve B occupies in relation to the bowl or whether it extends part way into the same or is wholly outside. In any case a close connection or joint is made.

If desired, two instead of one loose or separate hook member like 4 may be used, and the method of fastening the said members would be the same as in the case of one alone.

20 What I claim as new, and desire to secure by Letters Patent, is—

1. The coupling for water-closet bowls consisting of a sleeve having a hook integral therewith and a channel constructed to engage a removable hook at different points

therein, in combination with a removable hook embedded in said channel, substantially as described.

2. The sleeve, substantially as described, having an integral hook projecting from its inner portion, and a longitudinal channel on its outside and encircling threads, in combination with an independent hook locked in said channel beneath the engaging portion of the said threads substantially as described. 35

3. The hook-supporting sleeve having a longitudinal channel on its outside and a thread around said sleeve across said channel, in combination with a hook locked in said channel and embedded therein beneath the thread crossing the same, whereby connection between hook and sleeve is made without threading the back of the hook, substantially as described.

Witness my hand to the foregoing specification this 10th day of December, 1897.

JOSEPH H. GLAUBER.
